CLAIM

The ornamental design for an air conditioner, as shown and described.

DESCRIPTION

FIG. 1 is a front perspective view of the front, right, and top sides of an air conditioner showing our new design;

FIG. 2 is a front perspective view of the front, right, and bottom sides thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and,

FIG. 8 is a bottom view thereof.

The broken lines shown represent unclaimed subject matter of the air conditioner and form no part of the claimed design.
